UNITED STATES PATENT OFFICE.

JOHN R. HUSSEY, OF INDIANAPOLIS, INDIANA.

FIREPROOF DOOR AND THE LIKE.

948,450.

Specification of Letters Patent.

Patented Feb. 8, 1910.

Application filed July 13, 1908. Serial No. 443,305.

To all whom it may concern:

Be it known that I, JOHN R. HUSSEY, of Indianapolis, county of Marion, and State of Indiana, have invented a certain 5 new and useful Fireproof Door and the Like; and I do hereby declare that the following is a full, clear, and exact description thereof, reference being had to the accompanying drawings, in which like numerals 10 refer to like parts.

The object of this invention is to provide an improved fireproof structure, such as a door or the like.

The invention is made with reference to 15 doors between buildings or parts of buildings mounted in such a manner as to close automatically when influenced by the heat of a fire.

One purpose of the invention is to make 20 the door not only fireproof but also light and durable.

The chief feature of the invention consists in making a door out of a central reinforcing means, preferably of wire fabric 25 or sheet metal, and securing on each side thereof sheets of mineral wool or other non-combustible material whereby the central portion will maintain the rigid and durable form of the door while the mineral wool 30 will protect the central portion of the door from fire and heat and prevent the destruction of the door.

Another feature of the invention consists 35 in the means for securing the mineral wool to the central portion. Therefore, I build up the door with a central reinforcing sheet, as a plane and uniformly on each side thereof I secure a number of asbestos or other non-combustible panel strips in rectangular 40 form and opposite each other to divide the door on each side into sections. These strips are secured by bolts or rivets that pass through the asbestos strips and the central portion of the door. Within the spaces thus 45 formed the layers of mineral wool are placed and sheets of tin are then secured to the structure to hold the mineral wool in place and protect it from water.

While the door may be made of only one 50 reinforcing strip or sheet, it may consist of several such sheets with non-combustible material secured between them and on both sides of each.

The full nature of the invention will be 55 understood from the accompanying draw-

ings and the following description and claims.

In the drawings Figure 1 is an elevation of a fireproof door with the left-hand two sections thereof complete, a third section 60 with both the tin covering and mineral wool removed from one side. Fig. 2 is a section thereof on the line 2—2 of Fig. 1. Fig. 3 is a door made up of a plurality of metal reinforcing sheets, the right hand end being 65 broken away. Fig. 4 is a view partly in perspective and partly in section of the lower left-hand corner of the structure shown in Fig. 1 excepting that the central metal plate is a perforated sheet of metal instead of the 70 wire fabric.

In Figs. 1 and 2 the central reinforcing means consists of a wire fabric 10 and to that on each side I place narrow strips 11 of asbestos. These strips are arranged so as to 75 form the door into rectangular sections and recesses into which sheets 12 of mineral wool are placed on each side of the central metal fabric 10, then on each side of the door a sheet of tin 13 is placed and bolts 14 are 80 passed through the sheets of tin and strips of asbestos and the metal fabric, as shown, for securing the parts rigidly together. This, it is observed, makes a very strong and yet light door and one which will be fire- 85 proof. The tin will suffice to hold the mineral wool in place and that and the asbestos will protect the central metal sheet which will maintain the form of the door.

Instead of using metal fabric 10 for the 90 stiffening of the door a perforated metal sheet 15 may be employed, as shown in Fig. 4 or any other structure adapted to maintain the form of the door and hold the mineral wool and asbestos in place.

In Fig. 3 there is shown a plurality of metal sheets 16 between which layers of asbestos 12 are located. Asbestos strips 11 extend around the mineral wool and space the metal sheets 16 from each other, and the bolts 100 14 pass through the whole structure, as shown in Fig. 2.

What I claim as my invention and desire to secure by Letters Patent is:

1. A fireproof structure consisting of a 105 rigid member for maintaining the form of the structure, strips of asbestos or like non-combustible material on each side thereof to form recesses on each side of said rigid member, means extending through the rigid mem- 110

ber and the strips of asbestos for securing them together, sheets of mineral wool or like non-combustible material filling said recesses, and means for holding the mineral wool in place.

2. A fireproof structure including a rigid member for maintaining the form of the structure, strips of asbestos oppositely located on each side of said structure to form recesses, means for securing them together, sheets of mineral wool in said recesses, and

sheets of tin or the like secured over the outside surfaces of the asbestos and mineral wool, substantially as set forth.

In witness whereof, I have hereunto affixed my signature in the presence of the witnesses herein named.

JOHN R. HUSSEY.
